WILLIAM M. VENABLE, OF PITTSBURGH, PENNSYLVANIA, ASSIGNOR TO BLAW-KNOX COMPANY, OF BLAWNOK, PENNSYLVANIA, A CORPORATION OF NEW JERSEY

METHOD OF AND MACHINERY FOR FORMING PAVEMENTS

Application filed February 7, 1928. Serial No. 252,528.

My invention relates to improvements in methods of and machinery for forming pavements, and finds practical application in the forming of concrete highways. In that particular application I shall describe it. The object is the production of a well compacted and durable pavement whose surface is relatively free of unevenness and irregularity, and free particularly of fortuitous areas of depression.

The accompanying drawings illustrate somewhat diagrammatically a road-building machine in which and in the operation of which my invention is embodied and achieved. Fig. I is a view of the apparatus in side elevation, resting in position for operation, upon the road rails of a road under construction. Fig. II is a view of the machine in plan from above. Fig. III is a view in vertical and transverse section, on a broken plane indicated by the line III—III, Fig. II. Fig. IV is a fragmentary view in vertical and transverse section, on the plane indicated at IV—IV, Fig. I.

My invention is applicable to the finishing of roadways, so as to obtain a proper spreading and smoothing of the concrete surface, with economy and without inconvenience. The primary concern is to produce from material which from the necessities of the case is non-uniform in composition and character a finished structure which is to the highest attainable degree uniform. In the practice of building concrete roads as it is now widely carried on, the concrete as it leaves the mixer is a mechanical mixture of stone, or other coarse aggregate, sand or other finer aggregate, cement, and water. This mixture is produced in batches; that is to say, a measured quantity of stone, a measured quantity of sand, a measured quantity of cement, and a measured quantity of water are stirred together in the mixer. If it were possible always to have raw material of exactly the same quality and of the same degree of fineness, and always by practical means of measurement to introduce exactly the same quantity of each component into each batch, the concrete produced would be uniform in consistency, batch after batch; and, of course, uni-

form concrete uniformly spread might be expected to afford a uniform road. In practice, however, it is impossible to obtain the raw material with perfect uniformity of size of particles, of degree of fineness, and of quality and character; and especially it is impossible, under practical conditions, to have uniformity in the quantity of water present in successive batches. Always there is moisture present in the sand and stone employed, and the moisture so present is variable in quantity. This variability of water content disturbs the proportioning of the batch, and, particularly in the matter of water component, has the effect of causing successive batches to be irregular beyond control in the matters of wetness and consequent fluidity. The water content of the completed batch as it is dumped from the mixer to the road surface may vary in a degree as great as 40% of the actually desired quantity.

In any case, the road-spreading operation requires a mixed concrete of great fluidity, a concrete whose water content is larger than necessary to effect setting. In the road-building operation so much of the surplus water as may be, should be removed, and this without removing with the water any appreciable part of the cement. The water content of the batches being variable beyond practical control, the removal of surplus water to leave a uniform body of concrete is difficult, because the quantity of the surplus is variable.

In road building it is necessary to employ machinery to spread the concrete; the slow and laborious hand spreading is inadequate, to meet the demands of speed and quantity. Concrete spreading machinery hitherto employed acts upon the concrete as though it were uniform in composition and consistency, and as though its water content always were the same. Machine-spread roads, when finished, are liable to manifest undesired irregularities of surface, and particularly depressions of surface, in which water will lie. The road on that account is inferior and is liable to more rapid deterioration.

Let it be assumed that two successive batches of mixed concrete are spread upon the sub-grade of a road, and that one batch has

25% more water in it than the other. Such a condition may easily exist in what is considered a well conducted job. Let it be assumed that the ratio of cement, sand, and stone used is 1:2:4, by volume. To mix these qualities of the solid components to the desired consistency, nine tenths of a cubic foot of water might normally be required; but, because of variations of the nature indicated, and chiefly because of variation in the moisture of the sand, these two batches differ in water content, and one has .22 of a cubic foot of water more than the other in each cubic foot of concrete.

It is manifest that, if the excess quantity of water in the wet batch is not worked out before the final spreading operation either the concrete in the portion of the road produced from the wet batch will be relatively porous, or some surplus water will escape or be worked out subsequent to the spreading operation. In the latter event, although the grade and the surface may have been correct, as left by the finishing machine, unequal settlement continues and the surface is found irregular half an hour later. In point of fact, such settlement actually occurs in very many cases in concrete roads as ordinarily built. The settlement is not uniform, but occurs in spots, so that the finished and hardened road presents an uneven surface, with numerous hollows, below the normal surface. The depth of these hollows due to this cause may be as great as one quarter, or even one half an inch. Although irregularities of surface are commonly produced by faulty finishing due to other causes, as well as to lack of uniformity in water content, I have perceived such irregularities of surface as cannot be eliminated by great care in the manipulation of devices now in use to be chiefly and primarily due to the variation in the water content of adjacent portions of the layer of concrete when freshly spread; and I have further perceived that adjacent portions of a road may differ in the matter of hardness and of friability, because of the differences in water content in the layer of concrete when spread. My invention lies in method and in machine which, instead of treating the concrete as though it were uniform in content and consistency from batch to batch as received from the mixer, spreads the concrete in a manner which renders it more instead of less uniform, and, removes from the concrete as it is spread a greater or less quantity of water, according as the particular batch is relatively wet or relatively dry; and so I produce a road of better uniformity, more satisfactory and more durable.

Referring to the drawings, a carriage 1 of suitable construction is mounted upon wheels 2, to travel along the rails 3, such as are customarily provided, both to carry the road-finishing machine, and to afford temporary walls or forms, between which the concrete is

spread, and, until it has hardened, confined. The carriage may be understood to be equipped with a prime mover. This ordinarily will be a gasoline engine, though manifestly it might be a prime mover of another sort, an electric motor, for example. In the drawings I show diagrammatically a sprocket wheel 4, which may be understood to be driven by the prime mover, and I have diagrammatically indicated operative connections with this sprocket wheel, for driving a shaft 5, mounted transversely in carriage 1. From the prime mover, and conveniently from the shaft 5, the carriage may be driven along the rails 3, through suitable driving connections; such, for instance, as those shown in Figs. I and II. Shaft 5 is equipped with a bevelled gear wheel 6, and a gear wheel 7 is integrated with one of the wheels 2 of the carriage. A connecting rod 8 equipped at one end with a bevel gear 9 and at the other with a worm 10, simultaneously engages gear wheels 6 and 7 and transmits rotation to the carriage wheel. The drive may be alternately forward, in the direction indicated by an arrow, Fig. I, or rearward.

The carriage is equipped with a plurality of rows of pressure shoes, in this instance two rows, which extend row by row transversely, and are spaced apart row from row in the direction of machine travel. The shoes are singly reciprocable in vertical direction. The shoes of the forward row are indicated by the numeral 11, those of the second row by 12. As best seen in Figs. II and III, these shoes are conveniently rectangular in plan; their nether surfaces are plane surfaces, or approximately plane surfaces, extending horizontally, or approximately horizontally, and conforming in these respects to the surface to which the concrete is to be shaped. Their forward lower edges are rounded. The shoes are situated side by side in close succession. The shoes are conveniently formed as steel castings. Those of the forward row are preferably wider in their front to rear extent than those to the rear. The shoes of the front row additionally are equipped with vertically standing plates 13 which constitute extensions of their front faces and which serve as limiting and pushing walls for the soft concrete. The shoes are vertically reciprocable between suitable guides, and these guides may be beams such as 14, constituting part of the carriage structure.

Means are provided for reciprocating the shoes 11 and 12, causing succeeding shoes in the row to rise and descend successively, and for effecting reciprocation throughout a range so limited and defined as to spread and press the concrete to the desired form and position. It is a matter of simple engineering to provide for such reciprocation of the pressure shoes, and the means which I

show will be understood to be exemplary of suitable means to that end.

The shaft 5 is conveniently mounted in an intermediate position in the length of the carriage, and at a substantial interval above the level at which the wheels engage the rails. The rearward of the two rows of pressure shoes is arranged directly beneath shaft 5. A second shaft 15 extends similarly transversely of the machine and in position vertically above the forward row. The shaft 15 is driven from shaft 5 and simultaneously with shaft 5, and means to that end, in the form of a sprocket chain drive 16, are diagrammatically indicated in Fig. I.

The shaft 5 carries a series of eccentrics 17 and the shaft 15 carries a series of eccentrics 18, and each eccentric is engaged by a block 19 (20), and to the blocks 19 and 20 the shoes 11 and 12 are severally pivotally secured. The eccentrics through such connections effect the limited reciprocation of the shoes, and manifestly the positioning of the succeeding eccentrics upon the shafts determines the intervals at which the individual shoes succeed one another in their rise and descent.

Shaft 15 extends at a somewhat greater interval than does shaft 5 above the level of the rails 3, the eccentrics 18 borne by shaft 15 are larger than those borne by shaft 5, and the driving connections are indicated to be such in character that shaft 15 rotates at slower speed than shaft 5. Accordingly the range of reciprocation of shoes 11 is greater than that of shoes 12, a feature which though not essential is desirable. The positions of the two shafts 5 and 15 are minutely adjustable in vertical direction, by means of the slot and bolt connections indicated at 21, between the standards in which they are journaled and the frame of the machine.

The construction and adjustment are such that each shoe 11 comes to the limit of its downward thrust with its nether surface slightly higher than the ideal surface to which the concrete is being shaped. This particular position, being by the means described adjustable, will be determined in each particular case according to circumstances, and primarily according to the thickness of the layer to which the concrete is to be spread. The shaft 5 is so minutely positioned in its vertical adjustment that the shoes 12 come to their limit of downward thrust in a surface more closely approaching, but still slightly higher than the ideal surface.

The shoes 11 are preferably of greater extent in front and rear direction than are the shoes 12. They are heavier, and, as has been explained, their range of reciprocation is greater.

To the rear of the shoes 12 the machine frame carries a beam 22 extending transversely across the width of the space be-

tween the wheels, whose nether surface is of considerable extent in forward and rear direction, and whose nether surface conforms to the ideal surface to which the concrete is to be spread. This position may conveniently be attained by mounting the beam for vertical movement between guides, backing it with springs 23, and causing it to bear at its ends upon the opposite rails 3. The beam 22 will ordinarily be shod over those surfaces which make contact upon the rails 3, and it may be shod over all its nether surface, which comes into contact with the concrete. The plates with which it is shod may be renewable and replaceable.

At the front of the machine guard members 24 are fixed. These afford in effect upward continuations of the vertical inner faces of the rails 3. At their forward tips they are turned and extend obliquely across the treads of the rails 3. These guard members hold the concrete and prevent it from spreading laterally, and they keep the rails clear for the advancing machine.

In operation the rails are set, the machine placed on the rails, and, the sub-grade having been properly prepared, concrete is dumped from the mixing machine in front of the finishing machine, and the finishing machine is advanced upon the roughly spread-out, mushy mass. As the machine advances, the shoes 11 and 12 work up and down, and in each row the succeeding shoes work successively: One descends, then the next, and the next; and presently they rise again and descend again in the same succession. The first row of shoes acts on the mass of concrete both by pushing and treading, and shapes it to a layer of approximately the desired thickness. The second row of shoes, acting in like manner, reduces it more nearly to the exact, desired thickness, and, finally, the beam 22 brings the layer to the ultimate desired thickness and gives to it its surface character.

The shoes 11, approximately flat over their nether surfaces and rounded at their forward edges, both press the concrete downward and push forward the surplus. There will be some flowing of the concrete rearward beneath the shoes 11 and some consequent rising of the mass to rearward of the down-pressed shoe. The shoe is however of sufficient length in the direction of travel, to prevent any considerable movement of that sort. The fact will be particularly noted that the concrete is more thoroughly worked beneath the plurality of vertically moving shoes than it would be, were the several shoes merged in a single and continuous bar, and more thoroughly than would be the case were such a single bar reciprocated horizontally in transverse direction. And in these respects the method is distinguished from that now commonly performed.

As the machine advances, the body of concrete immediately to the rear of the line of shoes 11 is at approximately the proper grade; the minute adjustment of the shoes 11 has, however, been such that the body is somewhat above that proper grade. The value of the excess will in a given case be proportioned to the thickness of the layer which is being spread.

Between the rows of shoes 11 and 12 there is a stretch of concrete, reduced approximately to grade, but which has not yet received its final shaping and finishing. The body of concrete in this stretch is in a state of constant, though slight, movement, imparted to it by the shoes reciprocating immediately to the front and immediately to the rear. The effect is to compact the mass, causing water to work upward and flow away. The component solid particles of the mass are not widely displaced. The operation is unlike that known as "puddling". There is no kneading of the mass. The particles rock and tip one upon another, they move apart and together again through very slight intervals, but there is no appreciable sliding. In consequence, the particles assume positions of closer fit, and the water alone percolates upward to the surface. If the concrete has a relatively large water content, the water will escape more freely, and that without carrying away any substantial amount of cement. And because of the rise and escape of water in this region, the body of concrete upon which the shoes 12 work is stiffer and firmer than that upon which the shoes 11 work. Furthermore, the compacting effect is greatest at the bottom of the layer. From that part the water is, by the minute movement described, in largest measure expelled. When then the shoes 12 have acted upon the layer, and the bar 22 has followed, the layer, although in its upper part it contains somewhat more water than in its lower part, will still not contain any such large quantity of surplus water as to cause any considerable amount of subsequent settling of the spread and compacted layer.

The shoes 12 as here shown are of less extent in the direction of carriage travel than the shoes 11. The beam 22 is of such extent in the direction of carriage travel that, as it holds down the now relatively stiff concrete, there is no flow of concrete to rearward beneath it and no consequent rise of concrete behind it.

The shoes 11 are of such dimensions, and preferably the shoes 12 also are of such dimensions and so related in their period of reciprocation to the speed of advance of the machine, that the areas pressed upon successively by each shoe are overlapping areas.

Necessarily it is true of the machine when operating in the manner described, that concrete gradually accumulates, not only in front of the row of shoes 11, but also in front of

the row of shoes 12. When such accumulations have increased to a considerable amount, the parts 11, 12, and 22 are raised bodily and brought to position again to rearward of the accumulation which had gathered immediately in front of the beam 22. This resetting of the work-engaging parts is, in the machine here illustrated, effected by lifting the whole carriage body and placing it again on the rails at a point to rearward. The machine is then caused to advance again, operating as before. In practice, in laying a road nine or ten inches thick, the machine will advance thirty feet or more, before the accumulations make resetting desirable. The machine then is reset five or six feet to rearward. Thus the accumulations are not wasted but are carried forward and incorporated in the road as it is progressively shaped and finished.

I call attention to the fact that in the operation of my machine there is no transverse racking strain exerted upon the rails 3. They stand firm at all times. This results in a better compacted body of concrete, more accurate cooperation of shaping instrumentalities, and a better job. Incidentally, deterioration of equipment is less rapid.

I claim as my invention:

1. The method herein described of spreading forward supplies of concrete heaped upon the sub-grade of a road and bringing the worked-upon body to desired contour, which consists in subjecting the mass step by step, and over successive longitudinally overlapping relatively narrow transversely fractional areas to vertical pressure and at the same time restraining it to rearward of such areas from upward flow.

2. The method herein described of spreading to desired contour concrete heaped upon the sub-grade of a road and removing from the spread-out concrete a content of superfluous water which consists in subjecting localized areas of the layer along two spaced apart parallel transverse strips to successive compressive strains.

3. In apparatus for spreading to layer form concrete heaped upon the sub-grade of a road, a transverse row of vertically reciprocable pressure plates, means for causing the said row of plates to advance upon and to engage immediately the heaped concrete, and means for reciprocating the pressure plates through a definite and predetermined range, the means for causing the plates to advance and the means for reciprocating the plates being correlated, whereby each plate in its advance exerts pressure over overlapping areas.

4. In apparatus for spreading to layer form concrete heaped upon the sub-grade of a road, a transverse row of vertically reciprocable pressure plates, means for reciprocating said plates in alternation through a definite and predetermined range, and means for causing the said row of plates to advance upon and

to engage immediately the heaped concrete, the means for reciprocating the plates and the means for causing the row of plates to advance being correlated, whereby each plate in 5 its advance exerts pressure over overlapping areas.

5. In a road-finishing machine, a carriage mounted on wheels and adapted to travel on a pair of road rails, two rows of pressure plates 10 mounted in the carriage and extending transversely of the direction of carriage travel and vertically reciprocable in their mounting, means for reciprocating successively through a definite and predetermined range the plates 15 within each row, and a broad transversely extending float beam arranged to rearward of the second row of pressure plates.

6. In apparatus for the shaping of a road surface to desired contour, a car mounted to 20 move forward upon spaced-apart rails, a row of vertically reciprocable pressure shoes mounted on said car, means for reciprocating said shoes in sequence between predetermined upper and lower limits, and a float beam 25 broad relatively to said shoes arranged to rearward of said row of shoes for the purpose of preventing the rise of the concrete to rearward of the shoes, the nether side of said beam presenting to the concrete a smooth surface of 30 desired profile.

In testimony whereof I have hereunto set my hand.

WILLIAM M. VENABLE.
